PRINTING PRESS FEEDER

Fred J. Dietrich, Lemay, Mo.

Application February 13, 1940, Serial No. 318,740

5 Claims. (Cl. 271—61)

This invention, generally, concerns conventional vertical printing presses, such as for example, the well-known Miehle press. More particularly, it relates to the feeder tables of these presses.

At present, such presses can print only a single sheet of predetermined size and color at one time.

One of the principal features of my invention is the provision of means whereby two sheets 10 of the same or different sizes or colors may be printed at the same time.

Also, in the printing of double tone stock, i. e. paper whose opposite faces are of different colors, it is practical with the use of my invention to run such stock in "work and turn" fashion, eliminating the necessity of electrotypes and an extra make-ready required in the present-day method of "work and back" printing.

Another important feature resides in the ability to cut more units of a predetermined size from a standard sized sheet or ream of stock.

Other advantages will be apparent or referred to in the description to follow, and in the accompanying drawing, which forms part of this specification.

In the drawing, wherein similar reference characters designate like parts throughout the various views,

Fig. 1 is a front elevation of one element of 30 the invention;

Fig. 2 is a side elevation thereof;

Fig. 3 is a rear view of the upper portion on an enlarged scale;

Fig. 4 is a plan view, partly in section, taken 35 on the line 4—4 in Fig. 2;

Fig. 5 is a perspective view of the complementary element of my invention;

Fig. 6 is a vertical sectional illustration of a portion of a feeder table, with my invention 40 applied thereto;

Fig. 7 is a combined plan and section taken on the line 7—7 of Fig. 6;

Fig. 8 is a diagrammatic illustration of the 45 invention on a conventional feeder platform, portions of the back pile guide being broken away;

Fig. 9 is a similar view, partly in section, being taken approximately on the line 9—9 in Fig. 8, including well known printing press mechanism, 50 shown in broken lines;

Figs. 10, 11, 12 and 13, which are drawn to scale, ($\frac{1}{8}$ inch equalling 3 inches), illustrate 55 diagrammatically the paper economy possible with the use of my improvement.

In vertical presses, the sheets are stacked on a table A, the uppermost sheet of the pile being fed into the press in a well known manner by feeder arms B, (Fig. 9). The pile is automatically maintained at the proper height by the usual mechanism, including a pair of racks C fixed to the underside of said table, the racks moving vertically in bearings or guides on the feeder platform D.

A back pile guide E, and right and left front pile guides F, properly align the sheets, and a centrally located blowhead G fluffs each successive uppermost sheet at the proper time, whereupon it is fed into the press. The front vertical face of the table has a groove or track H, which cooperates with the front pile guides in adjustments toward or away from the vertical center line of the table, for sheets of various sizes. The bases of the guides F rest on the platform D.

The structure thus far described is old and is embodied in most commercialized presses of the type herein concerned. It is not considered necessary therefore, to illustrate or describe it in detail.

The present invention contemplates no changes whatever in said arrangement. To accomplish its purposes however, two elements are added. The first of these, generally indicated 1, is a casting of aluminum or other light-weight material. The other, generally designated 2, is of similar construction.

The former includes a vertical portion 3, and an integral base position 4 provided with apertures 5, whereby it can be secured to the platform D by screws 6, (Figs. 8 and 9). The horizontal cross-sectional configuration of portion 3 is best shown in Fig. 4. It includes a relatively wide, heavy rib or tongue portion 7, and relatively thin lateral extensions 8, all merging into the base portion 4 as shown.

Near the upper extremity of member 1, two apertures 9 are provided to accommodate wires 10, which pass through them and are formed into loops 11 extending more or less diagonally across the recesses 12 formed by the rib 7 and extensions 8.

The ends 10a of the wires are brought under the heads of screws 13, a washer or the like 14 being interposed between the vertical portion 3 and said ends as shown. These washers are not essential, but being of soft material, they aid in mounting the wires rigidly. They also act as spacers, simplifying adjustments.

55 The contour of element 2 is best shown in Fig.

5. The recessed portion or groove 15 has a sliding fit with the tongue 5, and the groove-defining extensions 16 have a similar fit with the recesses 12. As shown particularly in Fig. 7, the extensions 16 project laterally beyond the margins of the members 6 in order to give the pile of sheets S thereon better support.

Figs. 6 and 7 illustrate two piles of sheets in feeding position. It is noted that the uppermost sheet of each pile lies a slight distance below the adjacent loop 11, the lowermost upon the table and upon said element 2. The sheets are so positioned that a corner of each pile fits a recess 12, the front guides F being adjusted to so maintain the pile.

The standard groove H is utilized in mounting the support 2, portion 11 of the latter seating within the groove, and the downwardly extending rib 18 serving to maintain the horizontal plane of the support. An inspection of Fig. 6 will clarify this arrangement. It is here noted that no change of position, or adjustment of any kind is required in the blow-head G, or in the standard equipment of the table.

In the operation of the feeding device augmented by my improvement, the blowhead G fluffs the uppermost sheet of each pile, the air blast passing through the apertures 9, causing said sheets to flutter upwardly against the loops 11, whereupon the feeder arms grip and transfer the pair of sheets to the press in the usual manner.

As previously described, member 1 is mounted on platform D with its vertical portion 3 spaced from the front of the table a sufficient distance to accommodate element 2. The extensions 16, together with a substantial body portion of said element, support the piles at the table-overhanging regions adjacent upright 3. The adjustable loops 11 control the sheets in the fluffing operation. Since the feeder arms B and their associated parts are designed to deliver sheets of a predetermined maximum size, they can obviously simultaneously deliver two sheets of a total size which does not exceed that maximum.

My improvement makes possible a considerable saving in the stock required for a particular job. For example, a bilthead or circular of the size shown in Fig. 10 is required. Under ordinary practice, four sheets of the size illustrated in Fig. 11 would be cut from standard stock, (Fig. 12). Such sheet, indicated at a, is of course halved along the line b after printing. Consequently, eight final sheets represents the maximum yield possible.

Reference to Fig. 13 will show that with my improvement, nine final sheets may be cut and printed from stock of the identical proportions.

Thus it is apparent that the various objects and purposes of my invention are attained without requiring any changes in present commercial equipment.

Obviously the embodiment shown and described admits of various modifications. Therefore, I do not wish to be limited to the precise details illustrated and described.

I claim:

1. In a printing press feeder, including a table, a blowhead, a stationary platform, front and back pile guides, rack bars for raising and lowering the table, the latter having a longitudinal groove or track in its front vertical face, means removably mounted in said groove, and complementary means removably mounted on said platform, adapted to support and control two piles of sheets during feeding operations, the former means comprising a sheet support provided with a tongue at one side thereof adapted to enter said longitudinal track, a groove at the opposite side thereof, and a longitudinal vertical rib depending from the under side thereof adjacent said tongue, and the latter means including a base portion and a vertical portion, the latter having a rib or tongue adapted to seat within the groove of said support.

2. In a printing press feeder, including a table, a blowhead, a stationary platform, front and back pile guides, rack bars for raising and lowering the table, the latter having a longitudinal groove or track in its front vertical face, a pile support removably mounted in said groove, and an angular member removably mounted on said platform, the vertical component of the angular member having a tongue portion, and said support having a co-operating groove portion.

3. In a printing press feeder, including a table, a blowhead, a stationary platform, front and back pile guides, and rack bars for raising and lowering the table, means removably mounted on said platform comprising a horizontal base portion and a perpendicular portion, the latter being provided with apertures near its upper extremity whereby compressed air emitted by said blowhead at regular intervals is caused to pass through said apertures.

4. In a printing press feeder, including a table, a blowhead, a stationary platform, front and back pile guides, and rack bars for raising and lowering the table, means removably mounted on said platform comprising a horizontal base portion and a perpendicular portion, the latter being provided with apertures near its upper extremity, a wire passing through each aperture and forming a loop, the latter extending diagonally a predetermined distance in a substantially horizontal plane, and means for adjustably mounting said wires on said perpendicular portion.

5. In a printing press feeder, including a table, a blowhead, a stationary platform, front and back pile guides, rack bars for raising and lowering the table, the latter having a longitudinal horizontal groove or track in its front vertical face, a pile support removably mounted in said groove, and an angular member including a horizontal and a vertical component mounted on said platform, the horizontal cross-sectional shape of said vertical component being complementary to that of said pile support, whereby the latter is adapted to slide vertically on the former whenever the table is raised and lowered.

FRED J. DIETRICH.
